UNITED STATES PATENT OFFICE

FRANK E. INGRAHAM, OF WELLINGTON, OHIO

DOOR-OPERATING DEVICE

Application filed March 10, 1928. Serial No. 260,631.

This invention relates to door operating devices embodying among other characteristics, means for actuating the same at remote points therefrom.

5 Another object of the invention comprehends means adapted to automatically reverse the direction of the doors.

A further object of the invention contemplates auxiliary switch members adapted to 10 manually control the actuating means whereby the disposition of the doors may be regulated.

More specifically stated the operating means is connected with a cut off mechanism 15 adapted to render the same inactive when the doors are swung to occupy desired positions.

With the above and other objects in view, the invention further consists of the following novel features and details of construction, to be hereinafter more fully described, 20 illustrated in the accompanying drawings and pointed out in the appended claims.

In the drawings:—

Figure 1 is a top plan view of the invention, illustrative of its connection with the doors.

Figure 2 is a diagrammatic plan view of the various circuits included in circuit with the operating means for automatically and 30 manually controlling the same.

Figure 3 is a side elevation of the invention.

Figure 4 is a sectional view taken on line 4—4 of Figure 3.

35 Figure 5 is a sectional view taken on line 5—5 of Figure 6.

Figure 6 is a sectional view taken on line 6—6 of Figure 5.

Figure 7 is a sectional view taken on line 40 7—7 of Figure 5.

Figure 8 is an elevation of a switch member.

Figure 9 is a detail view of a lever adapted for reversing the motion of the operating 45 means.

Figure 10 is a detail view taken through another portion of the reversing lever.

Referring to the drawings in detail, where-in like characters of reference denote corresponding parts, the reference character 10

indicates a plate member carried by and suspended from or otherwise supported by bracket members 11 adjacent the ends thereof which are in turn connected with the ceiling of a garage or other storage place requiring entrance closures. An electric motor 12 being carried upon one end and preferably upon the upper side of the plate member 10 and adapted to operate a threaded shaft 13 in reverse directions, the purpose of which 55 will be presently apparent. Said shaft being journaled at its opposite end within a bearing member 14 carried upon one end of the plate member 10 in opposed relation to that of the motor 12. Angle plates 15, 60 adapted for connection with the side edges of the plate member 10, are adapted to define a channeled groove 16 adapted to accommodate a shoe or foot 17, slidably mounted upon the upper side of the plate member 10. 65 A tongue 18, upstanding from the shoe 17, is bifurcated, as indicated at 19, to support a connecting block 20, provided with forwardly projecting apertured ears 21, adapted to accommodate the innermost ends of rod members 22, having connection with bracket members 23, carried upon the inner sides of companion doors 24. The threaded shaft 13 is extended through the side walls upon the 70 opposite sides of the bifurcation 19 in the tongue 18 of the shoe 17 and within the block 20 disposed in said bifurcation 19, whereby the threaded shaft not only provides the necessary connection between the tongue 18 and block 20 but which also causes simultaneous sliding movement of the same. 75

Brackets 25, slidably mounted upon the angle plates 15, are provided with openings 80 adjacent the extremities thereof and adapted to accommodate a shaft 27. The latter mentioned brackets being provided with channeled portions 28 adapted to effectively engage the angle plates and the underside of the plate member 10 in the manner as best illustrated in Figure 4 of the drawings. 85 Bearing members 29, depending from the undersides and adjacent the ends of the plate member 10, are provided with spring pressed balls 30, adapted for selective reception within pockets 31, provided adjacent the ends of 90 100

the rod 27. Compression springs 32 being arranged between the adjacent sides of the brackets 25 and the bearings 29. Set screws 33, extended within the extremities of the brackets 25 and within the openings 26 thereof, are adapted to rigidly engage the shaft 27. The uppermost ends of the bracket member 25 are located in the path of movement of the tongue 18 for the shoe 17.

10 The end of the shaft 27, adjacent the motor 12, is curved and offset as indicated at 34 and which terminates to provide an elongated plate 35 having a diagonally disposed slotted portion 36 adapted to accommodate a reverse lever 37 for the motor 12.

15 From the foregoing description and accompanying drawings, it is readily apparent that the motor 12, when set in motion, will rotate the threaded shaft 13 and cause the shoe 17 to slide within the channeled portion 16 defined by the relative arrangement of the plate member 10 and the angle plates 15. The tongue 18 of the shoe 17, upon engagement with either of the brackets 25, will shift 20 the rod 27 in a corresponding direction, and the latter, due to its connection with the reverse lever 37, will cause the motor 12 to rotate in an opposite direction. Such action will continue until the circuit connected with 25 the motor 12 is opened. Obviously, during such reverse operations, the doors 24 will be 30 opened and closed.

It is my intention to render the apparatus 35 automatic in operation and to effect such operation, I provide a compartment 38, preferably sunken within the drive-way leading or approaching the doors 24. A treadle 39, hingedly mounted, as indicated at 40, within the top of the compartment 38, is supported 40 beneath its opposite side by compression springs 41 within the compartment. A shaft 42, rotatably mounted within the compartment 38, carries a ratchet gear 43 adapted for engagement with a pawl 44 to restrict movement in one direction, is also adapted for 45 engagement with a pawl 45 operable by the treadle 39 through the instrumentality of a connecting rod 46 carried upon the underside thereof. A dielectric disk 47, carried upon 50 the shaft member 42 and adapted for simultaneous operation therewith, is provided with multiple contacts 48 upon diametrically opposite sides thereof adapted for contacting engagement with spring contacts 49 and 50, 55 arranged upon the opposed side walls of the compartment 38.

From the diagrammatic plan view in Figure 2 of the drawings, wherein I have illustrated the wiring circuit adapted to establish 60 communication between the treadle operating means and operating means per se. It is noted that the switch member 47, when shifted to occupy the position as illustrated in Figure 2 of the drawings to close the circuit 65 between conducting wires 51 and 52; the con-

ducting wire 51 being included in circuit with switches 53 and 54, the latter being connected in circuit with a source of current, as indicated at 55. The opposite terminal of the source of current energizes a magnet 56, the other pole of the magnet having connection with the remaining conducting wire 52. A pivoted switch member 57, when magnetized by the magnet 56, causes contacting engagement of the free end thereof with contacts 58 and 59 having connection with conducting wires 60 and 61 respectively. The wire 60 establishes communication between the contact 58 and source of current 55 through a lead wire 62 to the motor 12. The conducting wire 61 is also connected with the motor 12 whereby the motor circuit is completed.

70 A vehicle when approaching the doors 24 encounters the treadle 39 with one of the front wheels therefor. Depression of the treadle 39 will cause the switch 47 to occupy the position as illustrated in Figure 2 of the drawings and the aforementioned circuit will be completed. The doors 24 will then open, due to their connection with the operating means. 75 The rear corresponding wheel of the vehicle when depressing the treadle 39 will shift the switch member 47 to occupy the dotted line position, as illustrated in Figure 2 of the drawings, but the motor circuit will not be 80 open, due to the presence of a dog 63 which engages one end of the switch member 57 to 85 sustain the latter in the position shown.

85 The doors 24 when swung to their utmost open positions will actuate the reverse lever 37 for the motor 12 incident to the connection of the plate member 25 and shaft 27 therewith. The doors will then begin to close and the vehicle by this time is parked within the garage. When the doors have been completely closed and the reverse operating means for the motor 12 partially shifted in an opposite direction, the reverse lever 37 will be brought into contacting engagement with a lever 64 90 pivotally mounted, as indicated at 65, and which will bridge the space between contacts 66 and 67. The contact 66 being connected in circuit with the source of current 55 through a lead wire 68. The contact 67 being connected with a relay 69 through a contact wire 100 95 105 110 115 120 125 130

When the reverse lever 37 is shifted in an opposite direction from that as illustrated in Figure 2 of the drawings to actuate the lever 64, it is to be noted that the motor circuit will not be open, due to the fact that the lever 64 is provided with a hinge connection 71 at an appropriate point in the length thereof and which will prevent contacting engagement of the contacts 66 and 67 therewith.

Either of the switches 53 or 54 may be arranged within the house and the other within the garage, whereby the opening and closing actions of the doors may be operated independently of the treadle.

5 It is further to be noted that either of the switches 53 or 54, when opened, will prevent unauthorized ingress and egress to and from the garage, whereby the opening of the circuit simulates a lock.

10 The invention is susceptible of various changes in its form, proportions and minor details of construction, and the right is herein reserved to make such changes as properly fall within the scope of the appended claims.

15 Having described the invention, what is claimed is:—

1. A door operating device comprising a plate member supporting a motor adapted 20 for driving a rotatably mounted threaded shaft, angle plates carried by the plate member being adapted to define a channelled race-way, a shoe slidably mounted within the race-way being provided with an upstanding 25 tongue adapted for connection with the doors, bracket members slidably mounted upon the plate member and angle plates being disposed in the path of movement of the tongue, and a rod member carried by and operable in conjunction with the bracket members and 30 tongue being adapted to reverse the motor.

2. A door operating device comprising a plate member supporting a motor adapted for driving a rotatably mounted threaded 35 shaft, angle plates carried by the plate member being adapted to define a channelled race-way, a shoe slidably mounted within the race-way being provided with an upstanding tongue adapted for connection with the doors, 40 bracket members slidably mounted upon the plate member and angle plates being disposed in the path of movement of the tongue, a rod member carried by and operable in conjunction with the bracket members and tongue for 45 reversing the motor, and an elongated plate carried upon one end of the rod member adjacent a reversing switch for the motor and adapted to receive same within a diagonally disposed slot therein.

50 In testimony whereof I affix my signature.
FRANK E. INGRAHAM.
